UNITED STATES PATENT OFFICE.

HARVEY M. GERSMAN, OF CHICAGO, ILLINOIS.

EXPANDED SHEET METAL.

Application filed June 1, 1923. Serial No. 642,870.

This application is filed as a continuation, as regards common features of patentable subject matter, of my application, Serial No. 473,062, filed May 27, 1921.

- 5 This invention relates to improvements in expanded sheet metal for use more particularly as lathing for the reinforcement and retention of plaster and for other structural purposes.
- 10 The features of improvement are directed to the type of metallic lathing which is characterized by cells or voids of hexagonal outline.

The objects of the invention, briefly stated, are to provide expanded sheet metal which shall have highly effective clinching properties while at the same time reducing the loss of plaster by seepage, which shall be of less weight, considering the voids size 20 for size, than expanded sheet metal of the ordinary form, which shall be stiffer and better capable of withstanding the pressure incident to the application of plaster than expanded sheet metal of the ordinary form, 25 and which may be made to provide self furring effects, thereby to eliminate the necessity of the ordinary furring strips.

The webs or junction portions by which the strands are connected are, of course, arranged in rows and according to the present invention the junction portions are arranged to lie flat or substantially so, that is to say substantially symmetrically angular, relatively to the mean plane of the sheet 35 and the sheet is longitudinally corrugated whereby the strands extend from the junction portions at an angle to said mean plane.

Another feature of the invention consists in an arrangement of the corrugations 40 whereby the sheet is similarly formed on both faces. Another feature consists in the arrangement of the corrugations, whereby the parallel rows of junction portions are alternately offset relatively to the mean 45 plane of the sheet.

The invention also provides a novel relation 50 between the junction portions and the strands which involves a transversely concave formation of the junction portions and makes it possible to secure greater expansion without impairment of the strength of the strands or the security of their union with the junction portions.

The above features and details of structure appurtenant thereto are set forth at 55 length in the following description. Ex-

panded sheet metal in which the features of the invention are incorporated is illustrated, in a preferred embodiment, in the accompanying drawings wherein:

60 Figures 1 and 2 are, respectively, plan and edge views of the blank.

Figure 3 is a detailed plan view of the expanded sheet metal produced from the blank of Figure 1.

65 Figures 4 and 5 are detail sectional views in the planes 4-4 and 5-5, respectively, of Figure 3.

In all cases the strands 11 and the webs or connecting portions 12 delimit hexagonal cells or voids 13 and, as in the ordinary expanded metallic lathing, the hexagonal form of the cells is such that they are arranged in parallel rows whose axes are normal to and bisect the parts 12 as will appear by the 70 alternately arranged broken lines A and B.

The blank from which the expanded metal is produced is provided with slits which are in the direction of their length and are thereby arranged in rows disposed transversely of the sheet, the slits of one row being arranged in staggered or break-joint position relatively to the slits of adjacent rows; and the webs or junction portions of the expanded metal are substantially provided by the material which lies between the ends of the adjacent slits of the rows and between the alining slits of the alternate rows.

80 The expanded metal is formed with corrugations which are normal to the transverse rows of slits and in the preferred embodiment disclosed are arranged whereby the rows of junction portions, these forming the apices of the corrugations, are offset alternately at opposite sides of the mean plane of the sheet. The corrugations are preferably formed in the blank which is expanded in the usual manner to produce the finished metal, the strands which project from each 85 junction portion being pulled laterally outward relatively to one another. Consequent to the corrugation and the expansion of the blank the webs will be more or less flat, that is to say symmetrically angular relatively to the mean plane of the sheet, accordingly as the ends of the slits in the blank lie near to

90 lines C through the longitudinal centers of the webs, that is to say the central axes of the webs at right angles to the axes of the 100 rows A and B. The best results are obtained 105 by having the central portions of the webs of 110

rows at the same side of the sheet in a common plane and for this purpose the ends of the slits in the blank terminate in coincidence with the longitudinal centers of the webs. 5 However, results substantially better in degree than is possible with expanded lathing of the ordinary construction may be obtained, within the scope and contemplation of the invention, in various cases where the webs or junction portions lie at an angle to their mean planes, the value of the results increasing with the approach of the central portions of the junction portions to exact co-planar relation. 10 While very good results may be obtained in cases where the webs or junction portions are truly flat throughout their extent, the best results are obtained where, as shown, the junction portions are substantially flat, 20 that is to say symmetrically angular relatively to the mean plane of the sheet while yet being slightly concave in the transverse direction of the sheet, that is to say the direction at right angles to the rows A and B, and the slits are extended slightly at their ends into concave areas in which the junction portions are included. Stated otherwise, in order to secure the best results, the sheet is provided with shallow minor corrugations parallel and inverse to the corrugations above described and these minor corrugations are formed along the junction portions, the ends of the slits being extended slightly into the minor corrugations. The 30 minor corrugations are incorporated in the blank and are indicated at 14 in Figure 2. In connection with the extension of the ends of the slits into the corrugations 14, these latter are effective as the blank is expanded to provide for the formation of ridges 15 in the strands closely adjacent their lines of union with the junction portions and extending in the transverse direction of the strands. In each pair of adjoining strands 40 which extend from the same junction portions the ridges 15 increase in height from their mean to their extreme ends and, being thus produced by the deformation of the strands consequent to the expansion of the blank, prevent the development of stresses incident to such expansion which might otherwise result in the partial rupture of the strands along their lines of union with the junction portions. It follows that by 50 virtue of the minor corrugations 14 the slits may be made longer with resultant larger voids in the expanded metal than would otherwise be possible. In this way a greater degree of expansion with a consequent reduction in weight is secured while at the same time the strength of the expanded metal sheet is not impaired. In fact the ridges 15 serve as reinforcements for the strands and tend to increase the stiffness and pressure 60 resisting quality of the sheet, while the thrust

resisting area of the junction portions is not substantially reduced.

Expanded sheet metal embodying the features of the invention may be produced from a blank of the same initial form that is used 70 for the production of expanded sheet metal as heretofore known, that is to say, a blank having straight slits whose ends coincide with the longitudinal central lines of the webs. These features are shown in Figures 75 1 and 2 which also show the blank as corrugated in accordance with the invention. By virtue of what may be termed the major corrugations the webs of rows B lie in an upper plane and the webs of rows A lie in 80 a lower plane. By virtue of the minor corrugations 14 the webs are transversely concave to a slight degree. The length of the slits is such that they are extended slightly 85 at their ends into the minor corrugations 14.

The major corrugations are maintained in the expanded lathing and, with the end of the slits coincident with central longitudinal axes of the webs, the webs are maintained in 90 relatively the same planes as in the blank, the pull of the strands being equalized at both ends of the webs.

In the expanded sheet the strands extend in inclined or angular directions athwart the mean plane of the sheet and present the 95 greatest effective area to resist the thrusts incident to the application of the plaster. This will be apparent when it is considered that the planes of the strands substantially coincide with lines parallel to the axes of 100 the rows A and B in the mean plane of the sheet. The depths of the major corrugations will be such as to insure good clinching and keying effects while at the same time all, or nearly all, of the area of the webs and 105 the strands is utilized to resist the thrusts incident to the application of the plaster, thereby avoiding cutting through the plaster and minimizing the loss and waste of plaster by seepage. If desired the major corrugations may be made sufficiently deep to serve 110 as furring strips at either side of the sheet, a self furring quality being thereby provided.

It will be understood that the arrangement of the end of the slits in coincidence with the central longitudinal lines C of the webs is a preferred but not an indispensable feature of the invention and that superior effects are, in any case, obtained by the arrangement of the rows of webs to lie alternately at opposite sides of the mean plane of the sheet with the webs presented more or less flat.

It will, of course, be understood that the greater the surface area of the sheet occupied by the webs and the strands the less will be the number of voids per unit of area and hence the less will be the weight of the sheet per unit of area. Consequently the 125 130

present invention, providing as it does for an increase of the surface area of the sheet occupied by the webs and strands, enables a material saving in the amount of metal required for the production of a given area of expanded lathing. It will also be understood that while it is preferred to provide the minor corrugations 14 the invention is not to be regarded as limited to the provision of such corrugations since good results may be secured in cases where they are not employed.

In connection with the appended claims it will be understood that the transverse direction of the sheet is taken as being the same as the longitudinal direction of the voids, i. e., the direction of the slits in the blank, and the longitudinal direction of the sheet is taken as being the direction at right angles to the longitudinal direction of the voids.

Having fully described my invention, I claim:

1. Expanded sheet metal having strands and junction portions delimiting hexagonal voids wherein the voids and junction portions are disposed in rows extending longitudinally of the sheet and the sheet is longitudinally corrugated, the strands by virtue of the corrugations extending from the junction portions at an angle to the mean plane of the sheet and the junction portions being transversely concave relatively to the face of the sheet to which they are presented and also being substantially symmetrically angular relatively to said mean plane.

2. Expanded sheet metal having strands and junction portions delimiting hexagonal voids wherein the voids and junction portions are disposed in rows extending longitudinally of the sheet and the sheet is longitudinally corrugated and by virtue of the corrugations is similarly formed on both sides, the strands by virtue of the corrugations extending from the junction portions at an angle to the mean plane of the sheet and the junction portions being transversely concave relatively to the face of the sheet to which they are presented and also being substantially symmetrically angular relatively to said mean plane.

3. Expanded sheet metal having strands and junction portions delimiting hexagonal voids wherein the junction portions are disposed in rows which extend longitudinally of the sheet and such rows are alternately offset at opposite sides of the mean plane of the sheet and said junction portions are also transversely concave relatively to the face of the sheet to which they are presented.

4. Expanded sheet metal having strands and junction portions delimiting hexagonal voids wherein the junction portions are disposed in rows which extend longitudinally of the sheet and such rows are alternately

offset at opposite sides of the mean plane of the sheet and the junction portions in at least one of the offset planes are transversely concave relatively to the face of the sheet to which they are presented.

70

5. Expanded sheet metal produced from a blank having slits in parallel transverse rows with the slits of one row in break-joint position relatively to the slits of the adjacent rows and corrugated longitudinally, whereby to offset the longitudinal rows of junction portions alternately at opposite sides of the mean plane of the sheet, the angle of the junction portions relatively to said mean plane being determined by and in accordance with the proximity of the ends of the slits to the central longitudinal axes of the junction portions.

75

6. Expanded sheet metal produced from a longitudinally corrugated blank having slits in parallel transverse rows with the slits of one row in break-joint position relatively to the slits of the adjacent rows and the ends of the slits terminating in line with the central longitudinal axes of the junction portions and the corrugations formed and arranged whereby to offset the junction portions alternately at opposite sides of the mean plane of the sheet, the junction portions also being transversely corrugated and the slits extending slightly at their ends into the corrugations of the junction portions.

80

7. Expanded sheet metal having strands and junction portions delimiting hexagonal voids wherein the voids and junction portions are disposed in rows extending longitudinally of the sheet and the junction portions are transversely concave while the strands have ridges transversely thereto and extending closely adjacent their lines of union with the junction portions.

90

8. Expanded sheet metal having strands and junction portions delimiting hexagonal voids wherein the junction portions are disposed in rows which extend longitudinally of the sheet and such rows are alternately offset at opposite sides of the mean plane of the sheet, the junction portions being transversely concave and the strands having ridges transverse thereto and extending closely adjacent their lines of union with the junction portions.

100

9. Expanded sheet metal produced from a blank having slits in parallel transverse rows with the slits of one row in break-joint position relatively to the slits of the adjacent rows and corrugated longitudinally so as to offset the longitudinal rows of junction portions alternately at opposite sides of the mean plane of the sheet, the blank also having corrugations along the junction portions inverse and parallel to the corrugations first named and having the ends of the slits extending slightly into the inversely corrugated portions.

120

125

130

10. Expanded sheet metal having strands and junction portions delimiting hexagonal voids wherein the voids and junction portions are disposed in rows extending longitudinally of the sheet and the sheet is longitudinally corrugated, the strands by virtue of the corrugations extending from the junction portions at an angle to the mean plane of the sheet and the junction portions having their angle to the mean plane of the sheet determined by and in accordance with the degree of proximity of the ends of the voids to lines longitudinally central of said junction portions. 30
11. Expanded sheet metal having strands and junction portions delimiting hexagonal voids wherein the voids and junction portions are disposed in rows extending longitudinally of the sheet and the sheet is longitudinally corrugated, the strands extending from the junction portions at an angle to the mean plane of the sheet and having ridges transversely thereto and extending closely adjacent their lines of union with the junction portions. 35
12. Expanded sheet metal having strands and junction portions delimiting hexagonal voids wherein the voids and junction portions are disposed in rows extending longitudinally of the sheet and the sheet is longitudinally corrugated, the strands extending from the junction portions at an angle to the mean plane of the sheet and having ridges transversely thereto and extending closely adjacent their lines of union with the junction portions. 40
13. Expanded sheet metal having strands and junction portions delimiting hexagonal voids wherein the voids and junction portions are disposed in rows extending longitudinally of the sheet and the sheet is longitudinally corrugated, the strands being bent laterally from the junction portions and by virtue of the corrugations extending at an angle to the mean plane of the sheet, the strands lying in planes which substantially coincide with lines parallel to the axes in the mean plane of the sheet of the rows of junction portions and voids. 45

In testimony whereof I affix my signature.
HARVEY M. GERSMAN.
